CENTRIFUGAL AIR CLEANER

Charles C. Whittaker, Pittsburgh, Pa., assignor to
Westinghouse Electric Corporation, East Pittsburgh, Pa., a corporation of Pennsylvania

Application December 11, 1948, Serial No. 64,795

4 Claims. (Cl. 183—80)

1

My invention relates, generally, to air cleaners and, more particularly, to cleaners of a type in which foreign matter is removed from air and other gases by centrifugal action.

In air cleaners of previous designs, the particles of dirt passed through the fan in the cleaner during the cleaning process. This caused erosion of the fan blades and also gave the particles an impulse in a direction which interfered with the efficient collection of these particles of dirt.

Prior cleaners also required that a relatively high percentage of the total volume of air be utilized for scavenging. Since this amount of air was discharged with the dirt, it was not available for cooling or other useful purposes.

An object of my invention, generally stated, is to provide an air cleaner which shall be simple and efficient in operation and which may be economically manufactured and installed.

A more specific object of my invention is to prevent the dirt removed by an air cleaner of the centrifugal type from passing through the fan which draws the air through the cleaner.

Another object of my invention is to reduce the amount of air required for scavenging a centrifugal air cleaner.

Other objects of my invention will be explained fully hereinafter or will be apparent to those skilled in the art.

In accordance with one embodiment of my invention, a skimmer ring and an annular jet are provided for discharging the particles of dirt from an air cleaner of the centrifugal type. The skimmer is so disposed that the dirt does not pass through the fan in the cleaner. The jet may be adjusted to discharge a maximum amount of dirt with minimum air wastage.

For a better understanding of the nature and objects of my invention, reference may be had to the following detailed description, taken in conjunction with the accompanying drawing, in which:

Figure 1 is a view, partially in elevation and partially in section, of an air cleaner embodying the principal features of my invention, and

Fig. 2 is a view, in plan of a portion of the structure shown in Fig. 1, a portion being broken away for clearness.

Referring to the drawing, an air cleaner, which may be of the centrifugal type such as disclosed in my copending application Serial No. 685,010, filed July 20, 1946, patented June 20, 1950, No. 2,512,401, comprises an outer sleeve 11 and an inner sleeve 12 which is separated from

2

the outer sleeve 11 by a space 13. The bottom of the outer sleeve 11 may be attached to a supporting plate 14 which in turn may rest on a suitable supporting structure such as the floor 5 of a locomotive cab (not shown). A flat disk 15 having a central opening 16 may be attached to the top of the outer sleeve 11. A similar disk 17 having a somewhat smaller central opening is spaced from the disk 15 and supported by a plurality of channel-shaped vanes 18 which may be secured in position by stud bolts 19, as shown in Fig. 2.

A motor 21 is disposed in the opening in the disk 17 and may be attached to the disk 17 by 15 stud bolts 22 which are threaded into a flange 23 provided on the housing of the motor 21. The motor 21 may be provided with a removable end cover 24. As shown, the top of the inner sleeve 12, which surrounds the motor 21, may be attached to the flange 23 on the housing of the motor 21.

As shown in Fig. 1, a fan 25, which is driven by a vertical shaft 26 of the motor 21, is so disposed at the bottom of the inner sleeve 12 that air which 25 enters the cleaner between the spaced disks 15 and 17 is drawn axially downwardly through the space 13 between the outer sleeve 11 and the inner sleeve 12 by the fan 25. As shown by the arrows in Fig. 2, the air enters at A tangentially to the vertical sleeves 11 and 12 and is then bent downwardly through an angle of 90°. Part of the dirt is removed by centrifugal action as the air flows through the 90° bend and is thrown against the inside of the outer sleeve 11.

As described in my aforesaid copending application, the vanes 18 are so disposed that the air is caused to whirl about the inner sleeve 12 as it travels downwardly through the cleaner, thereby removing the remainder of the dirt from the air. In this manner the foreign matter in the air, generally referred to as dirt, is thrown against the inside of the outer sleeve 11 by centrifugal action.

As shown in Fig. 1, the particles of dirt travel downwardly along the sleeve 11 until they come 45 to a skimmer ring 27 which surrounds the fan 25 and is spaced from the outer sleeve 11 by spacing members 28 disposed on bolts 29 which support the skimmer ring 27. As shown, the upper edge of the skimmer ring 27 is so disposed above the fan 25 that the dirt is prevented from passing through the fan 25. In this manner erosion of the fan blades is prevented.

If the opening between the skimmer ring 27 and the outer sleeve 11 were continued to atmosphere above the blades of the fan 25, the dirt

would not pass out but air would be drawn into the fan intake by the suction of the fan. To overcome this tendency, I have provided an annular jet 31 which communicates with the pressure side of the fan 25. As shown, the jet 31 is formed between the bottom of the skimmer ring 27 and the top of a collector ring 32 which is disposed below and spaced from the skimmer ring 27.

As shown by the arrows in Fig. 1, a portion of the air from the pressure side of the fan 25 flows through the jet 31 and, by its velocity, overcomes atmospheric pressure, entrains the dirty air stream and blows it to atmosphere in the same manner as feed water is forced into a boiler by a steam injector. The dirty air is discharged through an opening 33 provided in the base plate 14 between the collector ring 32 and an enlarged portion 34 of the outer sleeve 11. A deflector ring 35 may be provided for deflecting the dirty air from around the collector ring into the opening 33.

In order that the jet 31 may be adjusted to obtain maximum dirt recovery with minimum air wastage, vertical slots 36 may be provided in the outer sleeve 11 for the bolts 29 which support the skimmer ring 27. In this manner the ring 27 may be adjusted vertically to vary the size of the jet 31 between the skimmer ring 27 and the collector ring 32. Actual tests have demonstrated that the efficiency of the present cleaner is considerably higher than that of cleaners previously constructed since a relatively high percentage of dirt may be separated with a low percentage of air being required for scavenging.

Furthermore, as shown by the arrows in Fig. 2, only clean air passes through the fan 27, thereby preventing erosion of the fan blades. Also, the skimmer ring 27 functions more efficiently in removing the dirty air from the cleaner since the top of the skimmer ring is above the fan blades, thereby preventing the fan from giving the particles of dirt an impulse in a direction which interfered with the efficient collection of the dirt particles, as was done in previous cleaners.

From the foregoing description it is apparent that I have provided an improved air cleaner of the centrifugal type which is relatively simple in construction and which is highly efficient in operation. The present cleaner is particularly suitable for use in electric locomotives but is not necessarily limited thereto as it has numerous other applications.

Since numerous changes may be made in the above-described construction and different embodiments of the invention may be made without departing from the spirit and scope thereof, it

is intended that all matter contained in the foregoing description or shown in the accompanying drawing shall be interpreted as illustrative and not in a limiting sense.

5 I claim as my invention:

1. A centrifugal air-cleaner comprising spaced outer and inner sleeves having an air-passage therebetween, an axial-flow fan at the outlet-end of said air-passage for causing air to flow through said air-passage, inlet-means disposed at the inlet-end of said air-passage and comprising whirling-means for causing the dirt-laden inlet-air to whirl centrifugally as it passes axially through said air-passage, whereby to cause the dirt to be thrown against the inside of the outer sleeve, a spaced skimmer-ring having a skimming end disposed in closely spaced relation to the inside of the outer sleeve for skimming the centrifuged dirty air off of said outer sleeve as said dirty air moves axially therewith, said skimmer-ring being disposed in closely spaced relation around the outer periphery of the fan whereby the fan draws the cleaned air through the inside of said ring, injector-means using a small quantity of the outlet-air from said fan to move the centrifuged dirty air axially along the space between the outside of said skimmer-ring and the inside of said outer sleeve, and vent-means for discharging said injector-moved dirty air out of the air-cleaner and into the atmosphere.

2. The invention as defined in claim 1, characterized by said outer and inner sleeves being disposed so that the fan is at the bottom of said air-passage.

35 3. The invention as defined in claim 1, characterized by the skimming opening being adjustable.

4. The invention as defined in claim 1, characterized by said injector-means including a collector-ring which is spaced axially from the discharge-end of said skimming-ring, and said skimming-ring being axially adjustable whereby to adjust the relative sizes of the skimming opening and the ejector-opening.
